UNITED STATES PATENT OFFICE.

JOSEPH KLAMT, OF HOWELL, NEBRASKA.

SNOW-REMOVAL APPARATUS.

Application filed April 14, 1924. Serial No. 706,493.

To all whom it may concern:

Be it known that I, JOSEPH KLAMT, a citizen of the United States, residing at Howell, in the county of Colfax and State of Nebraska, have invented new and useful Improvements in Snow-Removal Apparatus, of which the following is a specification.

My present invention relates to means for clearing roadways and streets of snow; and it has for its general object to provide an apparatus designed more especially for handling new fallen snow, and embodying means for taking up and elevating snow and conveying the elevated snow laterally for discharge at one side of the path formed by the apparatus or for discharge into means for loading the snow into wagons or sleds.

Other objects and practical advantages of the invention will be fully understood from the following description and claims when the same are read in connection with the drawings, accompanying and forming part of this specification, in which:

Figure 1 is a side elevation of the apparatus constituting the preferred embodiment of my invention.

Figure 2 is a longitudinal vertical section of the same.

Figure 3 is a cross-section of the apparatus.

Similar numerals of reference designate corresponding parts in all of the views of the drawings.

In Figure 1, I show the front portion of a tractor which may be of the well known Fordson type or of any other type without affecting my invention. The said tractor is equipped with a motor driven wheel 1, and its front axle is designated by 2.

Among other elements my novel apparatus comprises an appropriate main frame 3, the forward portion of the said frame being wheel-supported at 4, and the rear portion of the frame being equipped with rearwardly extending arms 5 that have portions 6 arranged in straddling relation on the tractor axle 2 and fixed thereto by screws 7 or other appropriate means.

Fixed to and carried by the main frame 3 is an inclined elevator frame 8 in which is arranged an endless elevator 9 having transverse lifts 10. The sprocket belts of the said elevator 9 are mounted on sprocket gears fixed to lower and upper transverse shafts 11 and 12, journaled in the frame 8.

Journaled in the lower portion of the

frame 8 is a transverse rock shaft 13 to which is fixed a scraping shoe 14 extending transversely and adjustable vertically between the sides of said frame. At one end 60 and exteriorly of the adjacent side of the elevator frame 8 the shaft 13 of the shoe 14 is provided with a worm gear 15, Figure 1. Said worm gear 15 is meshed with a worm 65 16 on a shaft 17, and the said shaft 17 being journaled in bearings on the main frame 3 and being equipped with a hand wheel 18 at its rear end it will be understood that the shoe 14 may be adjusted and adjustably fixed with facility to meet different conditions of roadway and street as the same are 70 encountered.

A transverse shaft 19 is carried by the main frame 3, and by the said shaft is carried a sprocket gear 20, connected by a 75 sprocket belt 21 with a sprocket gear 22 on the shaft 12 to drive the endless elevator 9 from the shaft 19. The said shaft 19 is driven from the motor-driven wheel 1 of the tractor through a belt 23, a transverse shaft 80 24 having a wheel 25 engaged by said belt, and intermeshed spur gears 26 and 27 on the shafts 24 and 19, respectively, Figure 1.

When deemed necessary, a conventional 85 or any other appropriate tensioning device 28 may be used in association with the belt 23 to assure proper working thereof.

The endless elevator 9 in the use of the apparatus serves to convey upwardly and rearwardly the snow elevated from the roadway or pavement by a shoe 14, and from the forward stretch of the elevator 9, the snow is delivered over a transverse wall 32, Figure 2, to a transverse endless conveyor 33 equipped with spaced blades 34. The 90

sprocket chains of the transverse conveyor 33 are mounted on sprocket gears 35 on a shaft 36 and on sprocket gears 37 on a shaft 38. The shaft 36 is also provided with a miter gear 38' which is designed to be engaged alternately by reversely arranged 100 miter gears 39 on a sleeve 40 that is splined on a shaft 41 which is connected with the before mentioned shaft through the medium of sprocket gears 42 and 43 and a sprocket 105 belt 44, Figures 1 and 3. The sleeve 40 is provided with a circumferentially grooved extension 45, Figure 3, and connected with said extension is a handle lever 46 through the medium of which the sleeve 40 may be 110 adjusted endwise to bring about the movement of the upper stretch of the transverse

conveyor 33 in one direction or the other according to the side of the apparatus from which the elevated snow is to be discharged. In this connection it will be noticed that the transverse conveyor 33 is arranged in a transverse trough 50 and that the said trough 50 is provided at its ends with removable gates 51, one of the said gates 51 being removed when the snow is to be discharged from its side of the apparatus. It will also be noticed in this connection that each of the shafts 36 and 38 is provided with an auxiliary sprocket gear for the connection of the sprocket belt 52, the sprocket belt 52 being shifted from one side of the apparatus to the other and connections similar to those shown at one side of the apparatus being provided at such other side for use in conjunction with the discharge trough 53* which is susceptible of use on either side of the main frame of the apparatus. I do not, however, deem it necessary to illustrate said connections at both sides of the apparatus. With reference to this part of my invention it will be noted, however, that the main frame 3 is provided at opposite sides with cradles 54* in which is removably placed and supported the transverse shaft 53 of the endless conveyor 54 in the trough 53*, the said endless conveyor 54 having blades 55 and including sprocket belts which are passed around the shaft 53 and the second shaft 56 of the discharge trough and are connected to said shafts by sprocket gears 57 thereon. It will also be noticed in Figure 3 that the endless conveyor 54 is driven through the medium of the belt 52 which engages the sprocket gear 58 on the shaft 53.

It will be apparent from the foregoing that incident to the use of my novel apparatus, the forward movement of the apparatus through a fall of snow will clear through the snow a path or roadway corresponding to the width of the apparatus, the snow being elevated by the conveyor 9 and being moved transversely of the apparatus by the conveyor 33 to one side or the other of the apparatus according to the direction in which the conveyor 33 is driven, and the snow will be delivered through the open end of the trough 50 to the lateral discharge trough 53*, whereupon the conveyor 54 in said trough 53* will discharge the snow at one side or the other of the apparatus according to which side carries the trough 53*.

For the maintenance of the lateral discharge trough 53* in working position I also employ the rod 60 which is detachably connected at its inner end to the main frame 3 so that it can be used on either side of the apparatus.

Inasmuch as my apparatus is designed to handle newly fallen snow it will be apparent that the apparatus need not be unduly heavy, and that therefore the apparatus may

be worked through the snow with the expenditure of but little power.

I have entered into a detailed description of the construction and relative arrangement of the parts embraced in the present and preferred embodiment of my invention in order to impart a full, clear and exact understanding of the said embodiment. I do not desire, however, to be understood as confining myself to the specific construction and relative arrangement of parts inasmuch as in the future practice of the invention various changes and modifications may be made such as fall within the scope of my invention as defined in my appended claims.

Having described my invention, what I claim and desire to secure by Letters Patent, is:-

1. An apparatus for removing snow adapted to be used in front of and connected with and moved by a tractor, the said apparatus comprising a main frame the forward portion of which is wheel supported, an inclined elevator frame carried by the main frame, an endless conveyor arranged in said elevator frame, a shoe carried by the elevator frame at the lower end thereof, a transverse trough carried by the main frame and arranged to receive snow from the forward stretch of said conveyor and having removable end gates, a transverse endless conveyor arranged in said trough, a lateral discharge trough removably supported at its inner end on the main frame and detachable and shiftable bodily from one side of said main frame to the other, an endless conveyor in said lateral discharge trough, a transverse shaft journaled in the main frame and adapted to be rotated from a motor driven wheel of a tractor, driving connections between said shaft and the elevating and transverse conveyors, the driving connection complementary to the transverse conveyor being reversible, and a driving connection including a sprocket belt intermediate of the transverse conveyor and the conveyor in the lateral discharge trough, the sprocket belt of the latter driving connection being shiftable from one side of the apparatus to the other.

2. An apparatus for removing snow comprising an appropriately supported main frame, an elevator frame carried thereby and having sides, an endless conveyor in the elevator frame and between the sides thereof, a rock shaft journaled in the sides of the elevator frame adjacent to the lower end thereof, a shoe fixed to said rock shaft and disposed and adjustable between the sides of the elevator frame, a worm gear fixed on said rock shaft and arranged adjacent to but exteriorly of one side of the elevator frame, a shaft journaled on the main frame and provided with a handle, and a worm fixed to said shaft and intermeshed with said worm gear.

3. In an apparatus for removing snow, the combination of a main frame having cradles at its sides, a discharge trough disposed at one side of the apparatus and extending laterally from the main frame and detachable and shiftable bodily from one side of the apparatus to the other side thereof, a shaft journaled in the lateral discharge trough and removably seated in one of the said 10 cradles, means for transmitting rotary mo-

tion to said shaft, an endless conveyor in the discharge trough and connected with and driven by said shaft, and means interposed between and connected with the main frame and the outer portion of the discharge 15 trough for maintaining said trough in inclined position.

In testimony whereof I affix my signature,

JOSEPH KLAMT.
